UNITED STATES PATENT OFFICE.

FREDERICK G. SARGENT, OF GRANITEVILLE, MASSACHUSETTS.

WOOL-OILING MACHINE.

SPECIFICATION forming part of Letters Patent No. 224,044, dated February 3, 1880.

Application filed April 28, 1879.

To all whom it may concern:

Be it known that I, FREDERICK G. SARGENT, of Graniteville, in the county of Middlesex and State of Massachusetts, have invented a new and useful Improvement in Wool-Oiling Machines, of which the following is a specification.

The invention relates to machines for oiling wool preparatory to carding or other working.

10 The object of my invention is to provide a machine which shall be simple, durable, and effective, and which shall avoid the numerous defects which prior machines exhibit.

15 The nature of the invention will fully appear from the subjoined description, when considered with reference to the accompanying drawings, forming part of this specification.

20 In the accompanying drawings, in which similar letters of reference indicate like parts, Figure 1 is a top-plan view of my machine. Fig. 2 is an end view. Fig. 3 is a sectional view on the line A' B' of Fig. 1.

25 A is the tank in which the oil is placed and in which the cylinder B B revolves. C is the brush, which, touching the bars or cylinder, takes some of the oil brought up by it, and when released from contact with it throws the oil in a spray upon the wool passing beneath. This throwing down of the oil is caused by the resilience of the filaments of the brush, and may be increased by giving a reciprocal movement to the brush. This may be accomplished by means of the arms H H, 30 moved by the shaft D through the eccentric E to rock the shaft F, to which the brush is attached, or by moving the shaft F in a rocking manner by any convenient mechanism.

35 D is the shaft on which the cylinder revolves, which is driven in any suitable manner by the other wool-working machinery. E is the eccentric which actuates the rock-shaft F, to which the brush is attached. This shaft can be held in any position desired by the set-screws s, if it be disconnected from the moving machinery.

40 G G are the bed or foot-pieces, to which the tank is attached by screws g, which pass through holes in the foot-pieces G and into the body of the tank A. These holes in piece G may be elongated, if desired, to facilitate

the adjustment of the tank when the operator wishes to make the brush touch the edge of it.

45 H H are the arms connected to the rock-shaft, to which the brush is attached. These arms are made adjustable, so that the brush may be placed in any position desired. These arms are connected with the eccentric upon the shaft D and the rock-shaft F, so that when the shaft revolves the brush attached to the rock-shaft will be vibrated.

50 The cylinder may be made of wire-gauze or of bars formed of wire, as before mentioned, placed horizontally at an equal distance from and parallel to the shaft forming its axis. 65 By this construction the oil or grease is taken up to the brush between the meshes or between the wires in a greater and more uniform quantity than by a plain or smooth surface or roller, because it will be held in the meshes of 70 the gauze or between the wires, from whence it will be delivered upon the face of the brush more evenly than it would be from a smooth surface.

75 When a plain surface revolving through the oil is used to convey it to the brush, and the brush is brought in contact with it, the end or face of said brush will be sprung back by such contact, and the pressure being uniform, or nearly so, and continuous the oil will be swept 80 forward in a wave-like form, and the brush will, when removed from such contact, be found to have an excess of oil upon the side of the advance filaments or bristles, with very little among or between them. If, therefore, any 85 attempt be made to throw off the oil on the brush upon the wool, it will be thrown down in a few large drops or masses, because only the accumulation which was on the advance side of the brush will be disengaged, the capillary attraction of the brush holding fast the small amount which was taken between the bristles or filaments on the ends of the brush; or if any of the small portions of oil be thrown 90 from between the filaments by the jar given 95 the brush, or by the resilience of its parts, it will in no way remedy the unevenness caused by the larger masses from the front of the brush.

100 When my improved form of gauze or wire-bar cylinder is used the oil is brought up between the meshes or wires in drops or quan-

ties adhering to or between the wires, and the brush, being brought in contact with them, has its filaments or bristles separated as its end passes from one to another of the wires, 5 and a larger quantity of oil is taken between the filaments of the brush while so opened and separated, and no large quantity is swept ahead of the brush, because the oil is protected from such action by lying or passing between 10 the wires, and consequently, when the brush is removed from contact with the cylinder or bars, the resilience of its material or the action of the machine vibrating it throws down upon the wool a large number of small drops from 15 the ends of the filaments or bristles and no large quantities from its forward side.

The cylinder, when constructed of wire bars, may have the wire backed or re-enforced with flat bars of metal, to give them additional 20 strength and stiffness, if desired, without departing from the spirit of my invention.

When the cylinder is formed of wire bars the brush can be made stationary and placed near enough to the axis of the cylinder to have the 25 ends of the filaments of said brush come in contact with the bars and be sprung backward thereby; then the resilience of the bristles or filaments of the brush, as they pass off the bars, will throw down the oil without the use 30 of mechanism to rock or vibrate the brush.

The brush is made stationary by uncoupling the arm H, which connects it with the eccentric

35 tric, and putting a set-screw in the box in which it bears, or in any other convenient manner. The brush is made to touch the bars by adjusting the arms which support the shaft F; but when the cylinder is formed of wire-gauze the shaft F must be rocked downward, carrying the brush with it after it has touched the cylinder, thereby throwing down the oil taken 40 by the brush from the cylinder.

The brush can be made of bristles, or, as I prefer to make it, of wire or films of metal, as when so constructed it is more durable and does not so readily lose its resilience by 45 absorbing the oil.

What I claim as new and of my invention is—

1. The combination of the tank A, the wire cylinder B, formed of wire bars, and the brush 50 C, substantially as described.

2. The combination of the tank A, wire-bar cylinder B, and brush C, made of wire or filaments of metal, which, by a resilient motion, throws the oil taken from the cylinder directly 55 upon the wool, substantially as described.

3. The combination of the tank A, wire cylinder B, brush C, rock-shaft F, arms H H, eccentric E, and shaft D, as and for the purpose substantially as described.

FREDERICK GRANDERSON SARGENT.
